GRAVITY UNLOADING RAILWAY CAR

Albert A. Johnson, Kew Gardens, N. Y.

Application May 26, 1938, Serial No. 210,220

8 Claims. (Cl. 105—257)

This invention relates to improvements in railway cars and more particularly to a gravity unloading railway car for the shipment of citrus fruits and like loose articles in bulk form.

The main object of the invention resides in a railway car in which loose articles may be shipped in bulk form and the contents of the car unloaded without the usual labor expense which is involved in manually unloading a railway car, and which reduces the cost of marketing many principal raw foods.

Another feature of the invention is to provide a railway car for the shipment of loose articles in bulk form which relies upon the uninterrupted gravitational flow of the articles from the car during an unloading operation, and which unloading may be effected simultaneously through opposite sides of the car and thereby greatly expedite the unloading operation.

A further feature of the invention is the provision of a railway car having a novel form of chute into and through which articles such as oranges, grapefruit, lemons, potatoes, onions, cabbages, cucumbers, and the like, may gravitationally pass without causing injury thereto.

A still further feature of the invention is the provision of a gravity unloading railway car having discharge outlets in opposite sides and midway of the length thereof, and hinged flooring sections extending from the outlets to the ends of the car, which sections may be selectively raised to inclined positions to cause the load supported upon the floor sections to gravitate toward the discharge outlets, each floor section being provided with a novel construction of hinged floor extension held in adjustable bearing engagement with the adjacent end wall of the car to close the gap between the floor section and the end wall of the car caused by the arc of travel of the floor section when raised to prevent loose articles supported by the floor section from dropping over the outer end thereof.

A still further feature of the invention is to provide an inclined chute for railway cars in which the gravitational flow of articles down the chute may be started and stopped and controlled as to speed of flow.

A still further object of the invention is the provision of a self unloading railway car in which the above features are embodied without affecting the standard construction prescribed for the building of railway car chassis.

With these and other objects in view, the invention resides in the certain novel construction, combination and arrangement of parts, the

essential features of which are hereinafter fully described in the following specification, are particularly pointed out in the appended claims, and are illustrated in the accompanying drawings, in which,

Figure 1 is a side elevational view of my improved self unloading railway car with part broken away in section, the floor section being illustrated in raised position in dotted lines.

Figure 2 is an enlarged detail vertical sectional view on the line 2—2 of Figure 1, the left side chute being illustrated in position for use.

Figure 3 is an enlarged fragmentary vertical sectional view of one of the outlet chutes with the gate closures in open position.

Figure 4 is an enlarged horizontal sectional view on the line 4—4 of Figure 1 showing one of the chute slide closures in open position and the other in closed position.

Figure 5 is a fragmentary side elevational view of one of the chutes in position for use, the gate closures being in closed position.

Figure 6 is an enlarged detail vertical sectional view on the line 6—6 of Figure 5 with the gate closures in open position.

Figure 7 is an enlarged detail sectional view on the line 7—7 of Figure 4.

Figure 8 is a detail vertical sectional view on the line 8—8 of Figure 5.

Figure 9 is a fragmentary sectional perspective view of the outer end of one of the hinged floor sections, the same being shown in lowered position.

Figure 10 is a fragmentary side elevational view of a modified form of discharge chute.

Figure 11 is a detail vertical transverse sectional view on the line 11—11 of Figure 10.

Figure 12 is an enlarged vertical sectional view similar to Figure 11 but showing the chute extension in open position for use.

Figure 13 is a detail vertical sectional view through the prop spring hinge connection.

Figure 14 is an enlarged detail vertical sectional view on the line 14—14 of Figure 12.

Figure 15 is a detail vertical sectional view of a modified form of cable rest for the auxiliary floor extension member.

Referring to the drawings by reference characters, the numeral 10 designates my self unloading railway car in its entirety which includes 50 an insulated refrigerator box car body 11 mounted on a wheel chassis 12, the latter having the usual central longitudinal beam 13 extending the length thereof and to the ends of which the car couplings 14 are connected. The car body 11 is 55

provided adjacent each end thereof with a vertical partition 15 to provide an ice compartment 16, the same having communication with the interior of the car body through any form 5 of air circulating passages. Opposite sides of the car body are provided with centrally located door openings 17 normally closed by double hinged doors 18-19. Removable horizontally disposed boards 19 also close the door openings 17 to permit 10 opening of the doors 18 when the car is loaded, without fear of the articles piled therein flowing through the door openings, but the boards may be individually removed as the level of the car contents lowers adjacent the door 15 openings during an unloading operation, to eventually permit access to the interior of the car body. The construction so far described is present in standard refrigerator railway cars but I shall now proceed with a detailed description of 20 the novel features which in combination with the above construction, constitutes my invention.

The car body 11 is provided centrally thereof with two identical discharge chutes 20-20, the same being respectively disposed at opposite sides 25 of the center beam 13 and which open through rectangular box-like housings 21 which depend from opposite sides of the car body. A sill 22 is mounted longitudinally upon the beam 13 and extends the length of the open top of the discharge chutes 20. The top of the sill 22 terminates on a plane substantially even with the car floor presently to be explained. The top of the sill is beveled as at 23 in the direction of the chutes 20-20. In view of the fact that both 30 chutes 20 are of identical construction, a description of one will suffice for the other.

The chute 20 includes an inclined metal bottom wall 24 which extends from the sill 22 to the open side of the housing 21, and downwardly 40 and inwardly converging side walls 25-25 which all coact to guide articles passing thereover to a restricted rectangular shaped discharge outlet 26. The inner ends of the converging side walls 25 connect with vertical partition walls 27 which 45 extend transversely of the housing 21 and divides the same into separate compartments 28 and 29. Journalized in the end walls of the chute adjacent the top of the discharge outlet 26 is a shaft 30 to which is fixed a plurality of spaced 50 arms 31, the said arms coacting to provide an upper gate closure A. An actuating lever 32 is fixed to the end of the shaft 30 which extends into the compartment 29 and may be locked in various positions by releasable latch mechanism 33. Coacting with the upper gate closure A is a lower gate closure B which includes a shaft 34 extending across the chute bottom wall 24 below the plane thereof and journalized in the partition walls 27 with one end of the shaft 55 extending into the compartment 29 and having an actuating handle 35 fixed thereto, the said handle being held in adjusted position by releasable latch mechanism 36. Fixed to the shaft 34 at spaced distances therealong are arms 37 which 60 are offset with respect to the path of the arms 31 of the upper gate closure A but which coact with the latter to provide a double closure for the discharge outlet 26. When the lower gate closure B is in open position, the arms 37 thereof seat in grooves 38 provided in the metal bottom wall 24 of the chute. When the gate closures A and B are in closed position as shown in Figure 2 65 of the drawings, the arms 31 and 37 are parallel and provide a grill-like wall for restricting 70

the flow of articles from the upper hopper portion of the chute 20.

Hinged at 39 at the bottom of the chute 20 is a chute extension member 40, the same being of U-shape in cross section, which when in lowered position extends beyond the plane of the side of the car body to form an extension for the discharge chute. When not in use, the extension member 40 may be raised to a vertical position to lie within the housing 21 to enable the hinged housing door 41 to be swung to a closed position. When closed, the door 41 is held by any suitable releasable fastening means, such as lock bolts 42. Foldable link braces 43 act to support the weight of the chute extension 15 member 40 when the same is in lowered position for use.

A slat floor section or door 44 is slidably mounted in grooves 45 in the side wall of the car body and the adjacent side of the sill 22 for 20 closing the entrance to the chute 20. The door 44 for closing one chute 20 is movable to an open position by sliding the same longitudinally toward one end of the car body while the door 44 for the other chute is slidable to an open 25 position in a reverse direction. Each sliding door 44 may be actuated from the adjacent exterior side of the car body by mechanism now to be described.

Each door actuating mechanism includes a 30 pair of spaced longitudinal rack bars 45' on the underside thereof which respectively mesh with a pair of pinion gears 46 fixed to a transversely disposed shaft 47 suitably journaled and disposed below the plane of the inner side of the 35 bottom wall of the car body. The outer end of the shaft is square and countersunk in a recess 48 in the side wall of the car body to which a crank handle 49 may be fitted for imparting turning movement to the shaft and sliding movement to the door 44 through the meshing rack and pinions 45-46. The doors 44 are closed when the car is loaded to relieve the gate closures A and B of the pressure of the 40 contents of the car. Fixed stops 50 are provided on the bottom wall of the car body in the path of sliding movement of the sliding door 44 for limiting the sliding movement of the door to fully opened and closed positions.

Hingedly mounted within the car body as at 50 51 adjacent the entrance to the opposed chutes 20, are tiltable floor sections 52-52. The floor sections 52-52 and their associated hoisting mechanism are identical in construction, and a description of one will suffice for the other. 55

These floor sections 52 take the place of stationary sectional floor racks now used on top of refrigerator car floors.

Each floor section 52 includes a plurality of spaced transverse cleats 53 having depending 60 feet 54 which rest upon the bottom wall of the car body 11 when the floor section is in fully lowered position. Spaced longitudinal slats 55 are secured to the top side of the cleats 53 and provide a flooring which is open and spaced from 65 the bottom of the car body for ventilating and cooling purposes.

Hinged at 56 to the outer end of the floor section 52 is a flagelated floor extension plate 57 which extends upwardly and outwardly to 70 rest against the end partition or wall 15 to close the gap or space between the outer end of the floor section and the wall 15 when the floor section is raised to its unloading inclined position. The top edge of the extension plate 57 is notched 75

at 58 to receive anti-friction rollers 59 which ride directly against the inner side of the wall 15. Triangular shaped end flanges 60 having anti-friction ball bearings 60' mounted therein are provided at the opposite ends of the plate 57 and freely abut the side walls of the car body to close the gap at the corners between the car body and the floor section. The floor section 52 and the extension plate coact to provide a single foldable floor unit completely overlying the bottom of the car body from one end thereof to a point adjacent the entrance to the chutes 20 to prevent articles from falling between the hinged floor section and the bottom of the car body during raising of the floor section to inclined position.

Hoisting and lowering mechanism is provided for each floor section 52 and which includes a cable 61 having one of its ends fixed to an eye bolt 62 which is anchored to the floor section centrally at the outer end thereof. The cable 61 extends upward from the eye bolt 62 and passes through and bears against a fork member 63 extending outwardly from a plate 64 bolted to the inner side of the extension plate 57 adjacent the bottom thereof. The extension plate is provided with a series of spaced bolt openings 65 whereby the plate may be adjustably bolted in position. After passing through the fork 63, the cable snugly passes through an elongated guide eye 66 secured to the inner side of the plate 57 adjacent the top thereof. The guide eye 66 acts to hold the floor section against side rocking although one side of the floor section 35 may be weighted more than the other. In other words, the eye tends to prevent side tilting of the floor section at all times. A pulley 67 is provided at the top of the partition wall 15 over which the cable 61 passes, the said cable 40 passing down through the refrigerator compartment 16 and being enclosed in tubing 68. Mounted at the bottom of the car body centrally thereof is a pulley 69, the axis of the pulley being at right angle to that of the upper pulley 67 whereby the cable after passing over the pulley 69 may be led transversely to pass over a horizontal pulley 70 located adjacent one side of the car body. The cable 61 after passing over the pulley 70 extends toward the center of the car 50 body and is enclosed in tubing 71 which guides the cable into the compartment 28 of the housing 21 where a pulley 72 is mounted for the guiding of the cable to a winding drum 73. The winding drum 73 is fixed to a transversely disposed shaft 74 journaled in bearings 75, and fixed to the shaft 74 is a gear 76. A winding shaft 77 extends transversely of the car body to opposite sides thereof, the opposite ends of the shaft being square and countersunk in the sides of the car body, whereby a winding crank may be applied to either end of the shaft and manual rotation imparted thereto. Fixed to the winding shaft 77 and extending into the compartment 28 is a pinion gear 78 which has constant meshing engagement with one end gear of a gear train 79, the other end of the gear train having a gear which constantly meshes with the gear 76, thus rotation is imparted from the winding shaft 77 to the drum shaft 74 by means of the pinion gear 78, gear train 79, and gear 76. The gear train 79 acts to reduce the amount of manual crank effort necessary to hoist the floor section under a load of articles supported thereby. It will thus be seen that the winding station for raising the outer end of the floor unit is remote

therefrom and by winding the cable 61 upon the drum 73, a pull will be exerted upon the cable and the floor unit will swing upward as illustrated in dotted lines in Figure 1 of the drawings. By reason of the cable forcibly bearing against the fork member 63, the extension plate 57 of the floor unit will be forcibly held against the end wall 15, the pressure decreasing as the floor section moves upward and the gap between the outer end of the floor section and end wall 10 15 becomes greater. Thus the extension plate 57 cooperates with floor section 52 to provide a tilttable floor extending from the chutes 20 to an end wall of the car body.

If desired, a removable partition 80 may be set up within the car body inwardly of the hinged end of the floor section 52 to partition off the interior. Also, if desired, slideable vertical partitions may be supported by the hinged floor section 52 in the manner set forth in my co-pending application Serial No. 153,723.

Assume that a railway car 10 as herein constructed is loaded with oranges or other loose articles in bulk as illustrated in Figure 1 of the drawings. To effect an unloading of the car contents at the point of destination of the car, conveyors are provided beneath the discharge outlets 20 at opposite sides of the car. The doors 41 are unlocked and dropped to open position and a crank applied to the shafts 47 to impart rotation to the shafts for sliding the doors 44 to open position, whereupon any articles loaded in the compartment between the partitions 80 will drop into the wide inlet ends of the chutes 20. The chute extensions 40 are swung down to the position shown in Figure 2 and the gate closures A and B may be manually swung to open position to allow the articles to gravitate down the chute 20 and be discharged from the chute extensions 40 onto the conveyors. The flow of the articles down the chute may be controlled by the actuation of the gate closure A to adjusted position, and the flow stopped at any time by moving both gate closures to closed position. The doors 18 may be opened at the beginning of the unloading 45 operation and the planks 19 removed as the unloading progresses to allow entrance into the car, whereupon the partitions 80 may be successively lifted or removed and the hinged floor sections 52 successively raised to inclined positions 50 by the actuation of the hoisting mechanism to cause the loose articles supported thereby to gravitate toward the center of the car body and be discharged through the chutes 20. After the articles supported by each floor section have been 55 unloaded, the floor section is lowered to its normal horizontal position, and when the car has been entirely unloaded of its contents, the chute extensions 40, doors 44, 18 and 41 are closed and the car moved away from the unloading station.

By this method of shipping loose articles in bulk and unloading the same by gravity, the labor cost for unloading is eliminated for two attendants may take care of an entire unloading operation. Also, the cost of railway car demurrage is reduced, for the contents may be quickly unloaded and the empty car rolled away from an unloading station to make room for the rolling in and emptying of the next loaded car. All of these savings in time, labor, and cost of packaging 70 reduces the cost of marketing many of the principal food commodities.

Throughout the entire structural design of the railway car 10, I have eliminated any sudden drop of the articles as they gravitate to the discharge 75

end of the chutes, which avoids any damage caused by injury to articles of fruit which are subject to bruise.

In Figures 10 to 14 inclusive, there is shown a modified form of chute in which the chute bottom is adjustable to various inclinations to regulate the control of the gravitational flow of articles from the car body. In this modified form, like parts hereinbefore described are identified by the same reference characters.

In the modified form, I provide a metal chute bottom 100 which is hinged adjacent the sill 22 as at 101 and which extends outwardly adjacent the open front of the box-like housing 21. The outer edge of the chute bottom 100 is provided with spaced bearing knuckles 102 which turnably support a shaft 103 to which a chute extension member 104 is pivotally connected. One end of the shaft 103 extends into the compartment 29 and has a manipulating handle 105 fixed thereto. The chute extension member 104 is swung to a vertical position when not in use as shown in Figure 11 of the drawings and when in use, the same is dropped to the position shown in Figure 12 where it forms a projecting continuation of the chute bottom 100. Lock bars 106 are pivoted to the outer side of the chute extension member 104 and have their free ends outwardly offset as at 107 for seating in keeper members 108 fixed to the underside of the outer end of the chute bottom 100. The lock bars 106 are offset to clear the hinged joint between the extension member 104 and the chute bottom 100.

For bracing and adjustably supporting the lower outer end of the chute bottom 100, there is provided a pair of prop arms 109 which are fixedly connected to the shaft 103 so as to turn therewith. The lower ends of the prop arms engage ratchet bars 110 fixed to the bottom wall of the housing 21 and which extend transversely thereof. By actuating the handle 105, the prop arms 109 may be swung to various adjusted positions in engagement with the teeth of the rack bars 110, which cause the chute bottom 100 to be moved to and supported at various angles of inclination. Springs 111 carried by the shaft 103 act to constantly urge the prop arms 109 into engagement with the rack bars 110. In use, the chute extension member 104 is first swung down and locked by the lock bars 106 and keepers 108, after which the chute bottom 100 may be adjustably supported at the desired angle of inclination.

In Figure 15 of the drawings I have illustrated a modified form of cable seat which may be used in lieu of the plate 64 and fork member 63 hereinbefore described. In this modified construction a plate 112 is welded or otherwise secured to the lower portion of the flicor extension plate member 57 centrally thereof. The plate 112 has spaced outwardly extending ears 113 provided with a series of spaced alined bolt openings 114. A bolt 115 extends through any pair of alined openings depending upon the amount of pressure to be imparted against the extension plate member 57. A saddle member 116 is mounted on the bolt 115 between the ears 113 and has an eye 117 through which the bolt passes. The lower end of the cable 61 seats against the saddle 116 and imparts an outer pressure upon the extension member 57 to hold the same in an upwardly inclined position against the adjacent end wall of the car body to prevent articles from dropping beneath the slat flooring of the car body.

In the construction and design of my gravity unloading railway car I have borne in mind the

essential factors which are necessary for a commercial carrier of fruits, vegetables, and other easily injured loose articles, namely,

(1) Avoids as far as possible the dropping of fruits and vegetables onto horizontal surfaces. 5

(2) Space must be conserved between the outside bottoms of the chutes and railroads rails.

(3) Chutes must have sufficient inclination to permit a gravitational flow of products.

(4) The center beam which is standard in car 10 construction must not be disturbed.

(5) The car body must be so constructed as to permit cold air to flow beneath the floor from the ends toward the center.

Whereas I have illustrated and described my 15 invention as applied to railway cars, the same may be embodied in trucks, trailers, and other like hauling vehicles.

While I have shown and described what I consider to be the preferred embodiments of my 20 invention, I wish it to be understood that such changes in construction and design as come within the scope of the appended claims may be resorted to if desired without departing from the spirit of the invention.

Having thus described the invention, what I claim as new and desire to secure by Letters Patent of the United States, is:

1. In a railway car, a car body, an outwardly and downwardly inclined chute extending transversely of said car body having its inlet end opening through the bottom of said car body and its discharge end opening at a side of said car body, opposed upper and lower coacting hinged gate closures mounted adjacent the outlet end of said chute, each of said gate closures including a plurality of spaced parallel arms, the arms of one gate closure being staggered with respect to the arms of the other gate closure to enable the same to freely pass during pivotal movement to open and closed positions, recesses provided in the bottom wall of said chute to receive and countersink the arms of the lower gate closure when in fully open position, individual actuating means for said gate closures, and individual releasable latch mechanism for holding the individual actuating means in various positions of adjustment.

2. In a railway car, a car body, an outwardly and downwardly inclined unloading chute extending transversely of said car body having its upper inlet end opening through the bottom of said car body and its lower end opening at a side of said car body, said chute including a bottom wall hinged at its top, and means connected to the lower end of said bottom wall for supporting the same at different angles of inclination.

3. In a railway car, a car body, an outwardly and downwardly inclined unloading chute extending transversely of said car body having its upper inlet end opening through the bottom of said car body and its lower end opening at a side of said car body, said chute including a bottom wall hinged at its top, props hinged to the lower end of said bottom wall, and fixed rack bars with which the free ends of said props engage for supporting said bottom wall in various positions of adjustment.

4. In a railway car, a car body, an outwardly and downwardly inclined unloading chute extending transversely of said car body having its upper inlet end opening through the bottom of said car body and its lower end opening at a side of said car body, said chute including a bottom wall hinged at its top, and means connected to the

- lower end of said bottom wall for supporting the same at different angles of inclination, a chute extension member hinged to the lower end of said bottom wall for movement to a vertical position 5 when not in use to close the lower end of said chute, and interengaging latch means carried by said chute extension member and said bottom wall for supporting said chute extension member in coextensive relation to the lower end of said bottom wall to project beyond the plane of the side of said car body when the chute is intended for use.
5. In a self unloading railway car, a box car body having chute means centrally thereof, a pair 10 of floor sections respectively extending from opposite sides of said chute means to the opposite ends of said car body, each of said floor sections being hinged at its inner end adjacent said chute means, a floor extension plate hinged to the outer end of said floor section and extending upward and resting against the end wall of said car body, a hoisting cable having one end attached to the outer end of each floor section and rising upward and over a pulley at the top of the adjacent end wall, a bearing member projecting from said extension plate against which said cable forcibly seats to urge said extension plate against the adjacent end wall during a floor hoisting and lowering operation, and winding means carried 15 by said car body to which the other end of said cable is connected.
6. In a self unloading railway car, a box car body having a discharge chute, a floor section having its inner end hinged adjacent said chute 20 and extending to an end wall of said car body, a floor extension plate hinged to the outer end of said floor section and extending upwardly and outwardly, anti-friction rollers mounted in the top edge of said extension plate and bearing against the adjacent end wall of said car body, a hoisting and lowering cable having one end attached to the outer end of said floor section and rising upward and passing over a pulley at the 25 top of the adjacent end wall of said car body, a fork member extending from the lower portion of said extension plate and in which said cable is seated, whereby an upward pull upon said cable causes the extension plate to forcibly engage the adjacent end wall to close the gap between the floor section and the end wall when said floor section is raised to an inclined position, and winding means mounted on said car body to which the other end of said cable is 30 connected.
7. In a railway car having a box body and a discharge outlet in the bottom of said box body, a floor section hinged adjacent said discharge outlet and extending toward one end of said body, a floor extension member hinged to the free outer end of said floor section and extending upwardly and outwardly at an angle and resting against the adjacent end wall, end walls provided at the sides of said extension member for snug engagement with the side walls of said body, a cable having one of its ends fixed to the outer end of said floor section and extending upwardly therefrom, a bearing member extending inwardly from said extension member against which said cable forcibly presses, a guide element carried by said extension plate and disposed directly above said bearing member and through which said cable snugly passes, and winding means to which the other end of said cable is connected to facilitate the raising and lowering of said floor section.
8. In a railway car having a box body, a floor section hinged at one end and normally resting upon the bottom of said body, the free end of said floor section extending to one end wall of said body, a flagelated floor extension member carried by the free end of said floor section and extending upwardly against the adjacent end wall, and hoisting and lowering means connected to said floor section and acting to forcibly hold said flagelated floor extension member in engagement with the adjacent end wall of said body.

ALBERT A. JOHNSON.
